HANDLE FOR A FLOOR TREATING MACHINE OR THE LIKE

Arthur Herzog, Wallisellen, Zurich, Switzerland, assignor
to Diethelm & Co. AG, Zurich, Switzerland

Filed May 31, 1974, Ser. No. 475,031

Claims priority, application Switzerland Dec. 16, 1973

Term of patent 14 years

Int. Cl. D15—05

U.S. Cl. D15—65

Fig. 3

Fig. 1

Fig. 2

Fig. 7

FIG. 1 is a front perspective view of a handle for a floor treating machine or the like showing my new design;

FIG. 2 is a left side elevational view thereof;

FIG. 3 is a side view from the opposite side thereof;

FIG. 4 is a top view thereof on an enlarged scale;

FIG. 5 is a perspective top view thereof;

FIG. 6 is a rear view thereof; and

FIG. 7 is a bottom view thereof on an enlarged scale.

I claim:

The ornamental design for a handle for a floor treating machine or the like, as shown and described.
